Primary Examiner—Alan P. Douglas*Assistant Examiner*—Susan Moon Lee(74) *Attorney, Agent, or Firm*—Harness, Dickey & Pierce, P.L.C.(57) **CLAIM**

The ornamental design for a two-dimensional code reader, as shown.

DESCRIPTION

FIG. 1 is a front perspective view of embodiment for a two-dimensional code reader, showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front perspective view of the removed reading frame thereof; and,

FIG. 10 is a rear perspective view of the removed reading frame thereof.
